UNITED STATES PATENT OFFICE.

WALTER C. FISH, OF LYNN, MASSACHUSETTS, ASSIGNOR TO GENERAL ELECTRIC COMPANY, A CORPORATION OF NEW YORK.

METER.

SPECIFICATION forming part of Letters Patent No. 727,606, dated May 12, 1903.

Application filed September 24, 1902. Serial No. 124,648. (No model.)

To all whom it may concern:

Be it known that I, WALTER C. FISH, a citizen of the United States, residing at Lynn, in the county of Essex, State of Massachusetts, have invented certain new and useful Improvements in Meters, of which the following is a specification.

My invention relates to improved means for relieving the pressure exerted against their bearings by shafts, such as the vertical shafts in meters.

In electric meters of the ordinary construction the armature-shaft is vertically disposed. Owing to the accurate operation required of these meters, it is desirable that the friction between the shaft and its bearings be made as light as possible. In order to decrease this friction, I employ a symmetrical current-carrying coil in conjunction with an electro-

magnet system for the purpose of reducing the pressure between the shaft and its journal. One of these members is carried by the armature-shaft and the other by the frame of the meter.

In the accompanying drawings, Figure 1 is an elevation, with parts in section, showing one embodiment of my invention. Fig. 2 is a fragmentary view similar to Fig. 1, showing a modified form of my invention.

The casing of a wattmeter of ordinary construction is shown at 1, in which the vertical shaft 2, which carries the armature 3, is mounted.

4 represents the field-coils of the meter. A disk 5 and magnets 6, of the ordinary construction, for retarding the movement of the armature, are shown. At the top of the casing is placed an electromagnet 7. This electromagnet is formed like an inverted cup, the bottom 8 of which is circular and forms the yoke of the electromagnet. Rising from the bottom at the center is the core 9, which is cylindrical in form and carries at its top the enlarged cylindrical dish-shaped pole-piece

10. Between the cylindrical enlargement 10 and the bottom 8 is wound the coil 11 for energizing the electromagnet. The sides of the cup are turned in, so that a portion 12, which is annular in shape, is in the same plane with

the cylindrical enlargement 10. The magnetic flux of the electromagnet passes, there-

fore, in substantially radial directions between the center of the cylindrical portion 10 and the inner surface of the extension 12.

Carried at the upper end of the armature-shaft 2 is an annular coil 13. This coil is symmetrically wound and is so placed as to lie in a horizontal plane between the cylindrical portion 10 and the inner extension 12 of the magnet 7. Arms 14 are clamped or secured to the armature-shaft 2 in any desirable manner and support at their outer ends the coil 13. Brushes 15, supported in any suitable manner—as, for instance, by being mounted on a cross-arm 16, carried by the casing—contact with slip-rings 17, which are carried by the armature-shaft 2. These slip-rings convey current to the coil 13, and the brushes 15 receive current from any suitable source.

Preferably the current which energizes the coil 13 is the potential-current of the wattmeter, and the brushes, connections, coil, &c., form part of the resistance in the potential-circuit. The coil 11 may also be included in this circuit, if desired. I have not thought it necessary to illustrate in the drawings the details of the connections between the coil 13 and the slip-ring 17 nor between the brushes 15 and the potential-circuit of the meter. A recess 18 may be formed in the end of the cylindrical portion 10, if desired, in which the upper end of the shaft 2 may be guided.

In the construction shown in Fig. 2 the iron core 7, corresponding to the electromagnet 7 in Fig. 1, is carried by the armature-shaft, and the coil 13' is carried by the casing. In this construction the separate energizing-coil for the member 7' has been dispensed with. This member may be made a permanent magnet 9c or the coil 13' may be so proportioned as to energize the member 7'.

If the coils are properly proportioned and located, the passage of current through them will in either case tend to raise the armature-shaft. A variation of the amount of current passed through the coils will have, however, but slight effect on the displacement given to the shaft, as a very slight elevation of the coil in Fig. 1 or the member 7' in Fig. 2 will lift them out of the position of strongest effect upon the other member.

With my invention there is little liability of trouble due to any side strain, as the coil can be wound in a very symmetrical manner and as any slight imperfection in proportioning will have but very little influence in producing side strain. Another advantage of my construction is the practical absence of hysteresis.

While I have described the members 7 and 7' as being annular in form, this construction is not absolutely necessary.

My invention, while particularly useful in connection with meters, is not limited to use in that connection.

15 What I claim as new, and desire to secure by Letters Patent of the United States, is—

1. In combination, a casing or support, a shaft mounted therein, pressure-relieving means for the shaft comprising a magnetic flux-directing member having two pole-pieces, and a current-carrying coil member located between the pole-pieces of the flux-directing member, one of said members being carried by the casing and the other by the shaft.

2. The combination with a supporting member and a member to be supported, of a pressure-relieving device comprising a magnetic flux-directing member, and a current-carrying coil so located as to be acted upon by the

30 flux directed by said member, the flux-directing member being carried by one of said members and the current-carrying coil by the other member.

3. The combination with a meter comprising

ing a frame, a shaft journaled therein, a current-coil and a potential-coil, of electromagnetic means for relieving the pressure between the shaft and the frame energized by the current passing through the potential-coil.

4. The combination with an electric meter 40 having a frame and a shaft journaled therein and a current-carrying coil, of electromagnetic means for relieving the pressure between said shaft and frame energized by the current passing through said coil.

5. In combination, a frame member, a shaft member supported thereby, means for maintaining a horizontal magnetic flux, carried by one of said members, and a horizontal current-carrying coil mounted on the other member 50 in position to be acted on by said flux.

6. In combination, a casing or support, a vertical shaft mounted therein, pressure-relieving means for the shaft comprising a magnetic flux-directing member having one pole 55 in the form of a disk and the other in the form of a ring or washer surrounding the disk, and a current-carrying coil member located between the pole-pieces of the flux-directing member, one of said members being carried 60 by the casing and, the other by the shaft.

In witness whereof I have hereunto set my hand this 22d day of September, 1902.

WALTER C. FISH.
